Primary Examiner—M. H. Tung
Attorney, Agent, or Firm—Robert Jelks Ward**[57]****CLAIM**

The ornamental design for a retractable mouse pad with beads, as shown and described.

DESCRIPTION

FIG. 1 is a perspective view taken from the top, front, and right side of a retractable mouse pad with beads showing my new design, the retractable mouse pad portion is shown partially extended, and the broken line drawings of part of a computer and a mouse are for illustrative purposes only and form no part of the claimed design;

FIG. 2 is a top plan view thereof;

FIG. 3 is a front elevational view thereof, the rear elevational view is a mirror image;

FIG. 4 is a right side elevational view thereof, the left side elevational view is a mirror image;

FIG. 5 is a bottom plan view thereof showing the retractable mouse pad portion partially extended; and,

FIG. 6 is a perspective view taken from the top, front, and right side of a retractable mouse pad with beads showing my new design.

The retractable mouse pad with beads in FIGS. 1, 2, 3, and 5 is shown in a partially extended position.
